Primary Examiner — Sheryl Lane*Assistant Examiner* — Stacey L Hopkins(74) *Attorney, Agent, or Firm* — Che-Yang Chen; Law Office of Michael Chen(57) **CLAIM**

The ornamental design of a working light, as shown and described.

DESCRIPTION

FIG. 1 is a front perspective view of a working light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof in a fully unfolded state; and,

FIG. 9 is a perspective view thereof in a partially unfolded state.

The broken lines shown in the figures are for the purpose of illustrating portions of the working light which form no part of the claimed design.

1 Claim, 9 Drawing Sheets(56)
